SHINGLE

Norman P. Harshberger, Scarsdale, N. Y., assignor to Bakelite Building Products Co., Inc., New York, N. Y., a corporation of Delaware

Application March 14, 1931, Serial No. 522,671

20 Claims. (Cl. 108—7)

This invention, relating, as indicated, to shingles, is more particularly directed to an improvement in shingles of the type known as composition shingles.

5 Briefly stated, it is an object of the invention to provide as cheaply as possible an interlocking composition shingle which is especially adapted for re-covering jobs, however, the invention is not to be construed as limited to only re-covering old roofs, as the shingle of the present invention can be just as well used on a new roof.

10 Heretofore, shingles have been manufactured which have interlocking means and are capable of ready incorporation with the roof. The main difficulty with the shingles of the prior art has been the expense involved in providing dies and cutting machinery for complicated patterns, and also the ease with which the interlocking projections tear off from the main body portion of 15 the shingle. In most instances of interlocking projections on shingles the interlocking means, which I will refer to as tabs, have been of hook like formation, and such formation has rendered it exceedingly easy to catch the tabs and tear 20 them from the main body portion.

25 Another undesirable feature residing in most of the shingles of the prior art is that an undue amount of nailing is required which entailed both the labor of nailing and the expense of the 30 nails.

35 A further undesirable feature of the shingles of the patented art is that their shapes represented a radical departure from the shapes of conventional shingles with which builders are accustomed to work. Ordinarily, builders being men of mature age, are extremely opposed to adopting an article which is radically different and this is especially true where the article has the disadvantages enumerated above.

40 In many of the shingles of the prior art it is common practice to bend or curl certain portions thereof so as to provide an interlocking means. This presents a source of annoyance, as the shingle wears because of the weathering of the 45 outer surfaces of the shingle along the line of bend, that is, the composition is likely to break if bent upon itself, and even though this break does not show at the time of bending it is apt to show up after the shingles have been in use for 50 some time.

At present there are numerous shingles on the market and in many instances these shingles are provided with interlocking means. However, reversible interlocking shingles are quite rare, and 55 by reversible I mean reversible one way. Even

more rare, and in fact unknown prior to my invention, is a shingle which is reversible both ways, that is, a shingle which can be laid in courses starting at the ridge of the roof and the eaves thereof, and starting in either the middle of the 5 roof or the side edges thereof. As one skilled in the art will readily realize, such features in a shingle are most desirable in that the roofer does not have to plan his work ahead, but can start at any convenient point and finish the 10 roof. Starting from the top of the roof has numerous advantages among which are, first, the finished roof is protected against any possible injury which might occur from constant passage of the workmen over such finished portion. This 15 is especially dangerous where in a re-covering job the old shingles are liable to be forced through the new composition shingle if trod upon. Second, the roofer can easily nail a working support to the sheathing or old shingles, and this 20 can be removed as he continues down the roof, causing no injury to the roof and providing a very expeditious manner of supporting. Third, supports for the shingles to be used can be placed on the sheathing or old shingles and quickly 25 removed in a fraction of the time now required where such supports rest on the newly laid shingles. At present all work is done upon newly laid shingles and all materials are carried across such shingles in a sharp distinction 30 to the manner in which the shingle of my invention may be used.

It is, therefore, an object of the present invention to devise a shingle which will be free from all of the preceding disadvantages and yet one 35 which will be cheaper to manufacture.

The annexed drawings and the following description set forth in detail certain mechanism embodying the invention, such disclosed means constituting, however, but one of various 40 mechanical forms in which the principle of the invention may be used.

In said annexed drawings:—

Fig. 1 is a plan view of the preferred form of an individual shingle; Fig. 2 is a plan view of a 45 plurality shingles as shown in Fig. 1 as they appear when secured to a roof; Fig. 3 is a plan view of a modification; Fig. 4 is a plan view of a plurality of shingles as shown in Fig. 3; Fig. 5 is a plan view of another modification; Figs. 6 and 50 7 are plan views of modifications of an individual shingle; and Figs. 8, 9 and 10 are views of various methods of laying the shingle shown in Fig. 1.

Referring now to the drawings, and especially 55

to Fig. 1, it will be seen that my improved shingle in its preferred form comprises a body portion 20 of the general shape of a parallelogram with longitudinal edges 26 and 27 and another straight edge 28. The end of the shingle opposite the edge 28 is of irregular contour and consists of a tab 21 which is defined by an outer edge 29, this last named edge substantially paralleling edge 28 and being connected to the body portion 10 of the shingle by the edges 30 and 32, which, if continued, meet edges 26 and 27 at an angle. The remaining edges 31 and 33 are substantially parallel to the edges 28 and 29, and the length of the tab 21 is substantially equal to that of a slot 23 which is closely adjacent the edge 28. The slot 23 is preferably of a width which is greater than the thickness of the shingle so that the tab 21 may be readily received therein, and as previously stated, the slot extends substantially parallel and adjacent the edge 28 leaving a space suitable for nailing. It will be seen that only one nail 24 is required to hold the shingle in one definite position because of the cooperation afforded by the tab with the slot.

If Fig. 2 the above described shingle is shown as in assembled position on a roof, but of course it will be understood that the shingle may just as well be laid in other relationships, such as illustrated in Figs. 8, 9 and 10. The manner in which the roofs shown in Figs. 8, 9 and 10 are laid will be described more in detail as the description proceeds.

Referring now to Fig. 3, it will be seen that my improved shingle may comprise a main body portion 1 which is of the general shape of a polygon, and more specifically may resemble a rectangle with a tab projecting from one end. The main body portion 1 has two longitudinal edges 2 and 3 which extend in approximately parallel relation. One end of the shingle is at an angle to the longitudinal sides 2 and 3, thus presenting an edge 4, which, with the edges 2 and 3, form three sides of the shingle. The remaining edge of the shingle has a projection or tab 7 extending therefrom, and this tab has its outer edge 8 extending in substantially parallel relation to the edge 4. The portions 9 and 11 connect the edge 8 with the main body portion 1, and as the tab has a length which is less than the width of the shingle two edges 10 and 12 extend at angles to the longitudinal sides 2 and 3.

At that portion of the shingle 1 which is opposite to the tab 7 a slot 5 is provided for the reception of the tab of a shingle of the same configuration as shown. This slot 5 preferably has a width which is greater than the thickness of the shingle to be received therein, and a length which is preferably equal to the length of the tab 7 at its base.

Between the slot 5 and the edge 4 a space is left for nailing purposes, and as shown, a nail 6 is received in said space. Ordinarily, one nail is sufficient to hold the shingle in place, but of course, two or more nails may be used, depending mainly upon the size of the shingle.

As will be noted from Fig. 4 of the drawings, the shingle 1 is extremely easy to lay, it being merely necessary to insert the tab 7 of one in the slot 5 of a second and place a nail 6 approximately at the end opposite the tab of the first. All of this can be done in a fraction of the time usually required to lay interlocking shingles which make use of hook like projections and curled edges.

In Fig. 5 a slight modification of the shingle shown in Fig. 3 is illustrated and in this instance the shingle has longitudinal edges 14 and 15 which are of wave like formation to impart to the finished roof a rustic effect. This shingle is just as economical as the shingle shown in Fig. 3 as the curves are complementary and when the shingle is cut very little, if any, waste occurs. This shingle has a tab 16 corresponding to the tab 7, and an edge 17 corresponding to the edge 10. It is also provided with the slot 13 for the reception of the tab 16 of another shingle and can be laid in the same manner as described with respect to shingle 1 or 20.

In Fig. 6 a still further modification is shown, and in this embodiment the shingle 50 closely resembles the shingle 20 of Fig. 1, with the exception that the slot 60 extends to the edge 51, this edge being one of the substantially parallel longitudinal edges 51 and 52. The tab 54 is provided at one edge of the shingle and this tab is bounded by the edge 55 and the tapering edges 56 and 58 which connect the edge 55 to the offsets 57 and 59. The edge 55 is approximately parallel to the edge 53 and likewise the edges 57 and 59 extend approximately parallel to both of said edges. The tab, as shown, is of tapering formation but it is not absolutely necessary to form the tab in this shape, it being possible to provide a tab the full length of the slot 60, or a tab similar to tab 7 of the shingle 1, that is, one in which the connecting edges 56 and 59 extend in lines which are parallel to the edges 51 and 52.

In Fig. 7 a still further modification is shown in which the transverse edges of the shingle are of curved formation, which not only imparts a pleasing ornamental appearance but in addition renders the joint more effective against the down-wash when the shingles are laid horizontally. The modification shown has a body portion 35 and a tab 39 with longitudinal edges 36 and 37 which are approximately parallel. The shingle has the general shape of a polygon and the edges 36 and 37 are connected by a curved edge 38. At the opposite end of the shingle a tab 39 is provided, which is defined by the outermost transverse edge 40, connecting edges 42 and 43 and the offset edges 41 and 44. It will be noted that the outermost edge of the tab 40 is curved in substantially parallel relation with the edge 38, and this edge 38 has located adjacent thereto a slot 45 which runs approximately parallel to the said edge 38. The employment of wave-like shaped slots and/or tab edges as shown in this figure greatly facilitates the assembly of adjacent shingles, since it permits a small portion of the tab to partially engage the most accessible portion of the slot and subsequently the whole tab may be slipped into position.

In Fig. 8 one manner of laying the preferred embodiment of my shingle is shown, and briefly the method consists in laying columns 60 and 61, after which an overlapping column 62 is placed so that its longitudinal edges extend parallel to the edges of the shingles in the aforesaid columns 60 and 61. From this it will be seen that the roofer will be enabled to start at the ridge of the roof and lay the first shingle in the vertical column 60 and then lay the first shingle in the vertical column 61, after which a half shingle is started in the vertical overlapping column 62. The same operations are repeated as the roofer extends his work down the roof, and as a result the roof is laid from the ridge to the eaves, and the shingles which have been laid cannot be dam-

aged by subsequent working operations for the reason that the roofer has completed the work above him and need not operate upon a laid roofing surface, as is customary with all shingles prior to the present invention.

In Fig. 9 another method of laying the shingles is shown in which the columns 63, 64 and 65 are lapped in succession one upon the other. As a result the roofer can expeditiously lay the shingles without injuring those shingles placed in position, and additional supports for the roofer and the shingles with which he works can be placed upon the sub roof whether it be sheathing or old shingles without any possibility of damage to the laid roof. In the event that a diagonal effect is desired the method disclosed in Fig. 10 can be followed so as to present a pleasing ornamental effect. Here the shingles can be laid upon the sheathing 18', but in this instance the roof can be laid more quickly by beginning at the eaves. However the roof can be laid by beginning at the ridge by nailing the shingles in the middle of the nailing space, that is, the space between the slot 23 and the edge 28. In order to do this it is merely necessary to start a course at the ridge and then insert the succeeding lower course under the upper course, and nail each shingle in the middle of the beforementioned nailing space.

A distinct advantage derived from a shingle formed according to my invention is that the tab forms a lap which not only serves to lock one end of the shingle but in addition forms a water proof lap. Specifically, the tab of itself aids in preventing the admission of water through the joint to the sub roof.

The modification shown in Fig. 6 illustrates a slot which connects with one edge, and in this instance the slot is disclosed in its preferred form as a slot of substantial width and connects with one of the longitudinal edges. However, in some cases where a similar result is desired but it is not desired to extend the preferred form of slot to the shingle edge it is desirable to slit the shingle to form the remainder of the slot and this may be done by providing a small slit extending at approximately right angles to the slot 23 and edge 28 of the shingle 20.

In the embodiment shown in Figs. 1, 3, 5 and 7, it will be seen that a reversible shingle is provided which has three edges which can be used as a butt, thus enabling the roofer to start and finish his roof from any desired point, and this will be seen to be extremely advantageous in many roofs.

From the preceding description, it will be noted that I have provided a shingle in which as little as possible of the shingle surface is overlapped, thus rendering the shingle cheaper to apply. It will also be seen that the shingles of my invention have strong large tabs, thus avoiding the trouble incident to little tabs which tear off quite easily. It will also be noted that the tab is not hook like in formation and will, therefore, be received intact by the roofer regardless of how many times it has been handled. It will, of course, be understood that in an ordinary roofing job, and especially on steep roofs, shingles pass through many hands before being laid, and that ease of handling is an extremely desirable characteristic. As a further advantage it will be perceived that a small amount of nailing is required so that both labor and material are saved.

A more important advantage is that the shingle is not a radical departure in shape from the conventional shingles, and yet is capable of inter-

locking in permanent working relation. The interlocking takes place between two shingles in the same course and is not only a very easy operation but takes place as the shingles are being laid in a course. This enables the roofer to lay a much greater number of shingles than where he first lays a course, and then interlocks the succeeding course therewith.

In addition to the preceding advantages, it will be seen that my shingle is capable of being laid from the ridge of the roof downwardly and that it is reversible so that a roof can be started at practically any point. Many advantages flow from the ability to lay my shingles in a downward direction, outstanding among which is that that portion of the roof which has been completed is not touched again by the roofer or other workman, and that supports for the roofer and material may be provided in a fraction of the time now necessary to provide such supports.

Throughout the specification the subject matter relates to a shingle of the type known as a composition shingle, but obviously other materials may be used, such as metal or wood, and the same excellent results would be obtained.

The proportions as illustrated are not to be construed as limited to those shown in the drawings, since they may be varied almost indefinitely according to the design desired.

Reference has been made to a roof merely for the purpose of shortening the description, but of course it will be understood that the shingle described is just as capable of use as siding or weather boarding, as in a roof or any other analogous structure.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. A shingle having the general shape of a rectangular parallelogram, with two substantially straight edges, and with one of the other two opposite edges substantially straight and at right angles to said first named edges, the remaining edge being crooked and having an outwardly tapered tab positioned substantially centrally thereof, a slot spaced within and lying adjacent said substantially right angled edge, said slot having a length substantially equal to that of said tab.

2. A shingle having a slot and a tab, said slot extending substantially parallel and within one of the edges of said shingle, and said tab being positioned along an opposite edge thereof and comprising more than one half its length, said shingle being adapted to be laid with said tab in the slot of an adjacent underlying similar shingle, and said tab extending in the direction of the shingle course when laid.

3. A shingle adapted to be laid in courses in downward progression, said shingle having the general shape of a parallelogram comprising three substantially straight edges and a fourth edge of irregular contour comprising a tab, there being a slot spaced from an edge opposite said tab, and said tab having a length substantially equal to that of said slot, and engaging the slot of an adjacent underlying shingle in assembly.

4. A shingle having the general shape of a parallelogram with three substantially straight edges and a fourth edge of irregular contour there

- being an elongated slot spaced within one of said edges and extending substantially parallel therewith a major portion of the width of the shingle, and said irregular edge comprising principally a tab, said tab having a length no greater than that of said slot, two of said straight edges being parallel and the third straight edge extending at an angle to said two edges, said shingle being adapted to be laid in a line parallel with said parallel edges.
10. 5. A shingle having the general shape of a parallelogram with three substantially straight edges and a fourth edge of irregular contour, there being an interior slot spaced from one of said straight edges and said irregular edge comprising a tab, said tab having a length substantially equal to that of said slot, two of said straight edges being parallel and the third straight edge extending at an angle to said two edges, said shingle being adapted to be laid in a line parallel with said parallel edges, said slot extending at an acute angle to said line, and an edge thereof defining an edge of a shingle exposure in assembly.
15. 6. A shingle having the general shape of a parallelogram, with two substantially straight opposite edges, and with one of two other opposite edges straight and at substantially right angles to a first named edge, the remaining edge being crooked and comprising a tab of more than one half its length, a slot adjacent said substantially right angled edge, said slot having a length greater than that of said tab, and engageable with the tab of a similar overlying shingle in assembly.
20. 7. A shingle having the general shape of a parallelogram with three straight edges and a fourth edge of irregular contour, there being a slot spaced from one of said straight edges and said irregular edge comprising a tab, said tab having a length equal to that of said slot, two of said straight edges being parallel and the third straight edge extending at an angle to said two edges, said shingle being adapted to be laid in a line parallel with said parallel edges, and in successive courses, starting from a ridge of a roof and continuing downwardly.
25. 8. A shingle having the general shape of a parallelogram with three substantially straight full edges and a fourth edge of irregular contour, there being a slot spaced from one of said straight edges and substantially parallel thereto, said irregular edge comprising a tab, said tab having a length no greater than that of said slot, there being a nailing space between said slot and the full edge of the shingle from which it is spaced, and the location of said slot and tab permitting laying of a plurality of said shingles in assembly beginning at the high point of a surface and progressing downwardly.
30. 9. A shingle adapted to cover a roof from its ridge to its eaves, said shingle having the general shape of a parallelogram, means on said shingle for interlocking one of said shingles to another, said means comprising a tab and a slot, a nailing space between said slot and one of the edges of said shingle, the location of said means and nailing space permitting laying of said shingle beginning at said ridge and continuing in courses parallel to said ridge.
35. 10. A shingle with a locking means on one edge thereof consisting of a tapered tab the length of which is more than one half the whole length of an opposite edge, said tab being adapted to register with a slot, the length of said slot being equal or greater than that of said tab.
40. 11. A roof comprising substantially flexible shingles laid in courses, said shingles comprising units having the general shape of a parallelogram and having slots adjacent and within one of their edges, said slots having a length of more than one half the length of said edges and said units having opposite edges comprising tabs, said tabs having a length no greater than said slots and said shingles being laid with their tabs engaged with the slots of other adjacent shingles, and edges of said slots forming weather edges of the shingle exposures, and courses of said shingles being laid with the distance between adjacent edges of every first and third course being no greater than the length of said slots.
45. 12. A covering for a weather surface comprising courses of shingles, said shingles adapted to be laid in courses starting from the high point of said surface and progressing downwardly, and having locking means comprising irregular edges forming tabs, and slots spaced from other edges in interior portions of the shingles; adjacent shingles in a course being interlocked, with the tab-formed edge of one shingle overlying the slot-spaced edge of the adjacent shingle and with the tab of the overlying shingle inserted in the slot of the underlying shingle and driven fastening means along said slot-spaced edge and between the interlock and said slot-spaced edge passing through the underlying shingle.
50. 13. A shingle having an aperture at one side of its longitudinal center and adjacent one end of the shingle, said aperture having an endless wall, and a lock tongue projecting from the other side edge thereof and in transverse alignment with said opening.
55. 14. A shingle having a lock tongue projecting from one side edge thereof, and tongue-receiving means wholly surrounded by the material of the shingle and spaced transversely from and in transverse alignment with said lock tongue to receive a lock tongue of an adjoining shingle and permit said lock tongue to be positioned underneath the first mentioned shingle adjacent said tongue-receiving means.
60. 15. A shingle having a lock tongue projecting from one side edge thereof, and an aperture in the shingle adjacent its other side edge and in transverse alignment with said lock tongue, said aperture being adapted to have the lock tongue of an adjoining shingle passed therethrough and underlie the first-mentioned shingle adjacent said aperture.
65. 16. A shingle of polygonal formation having locking means at a forward end thereof and receiving means at the rearward end thereof, said locking means comprising a tab of more than one half the length of a shingle edge of which it forms a part, and said receiving means comprising an elongated interior slot spaced from the rearward end of the shingle and substantially coextensive with said tab and having an edge when exposed presenting a convex and a concave portion in relation to said rearward end, said convex portion of said slot edge being more rearward of the shingle with respect to the forward end thereof than said concave portion of said slot edge.
70. 17. A shingle of polygonal formation having a locking and a receiving means, comprising respectively a tab having a length more than one-half a shingle edge of which it forms a part and spaced from the two adjacent edges and an elongated slot spaced from an edge opposite the tab formed edge and substantially coextensive with

said tab for receiving the tab of a similar shingle, said tab having a forward edge of wave-like contour to facilitate the interlock between engaging shingles and said slot also having an edge of wave-like contour to be exposed and extending obliquely to the direction of the shingle course when laid.

18. A shingle of polygonal formation having a locking and a receiving means, said locking means comprising a tab of more than one-half the length of a shingle edge of which it forms a part and said receiving means comprising an elongated interior slot comprising a cut substantially coextensive with said tab and spaced from an edge opposite said tab formed edge, said shingle adapted to be laid with the tab of one shingle inserted in the receiving means of an adjacent similar shingle and with the shingle portion adjacent said tab overlapping the edge of said adjacent shingle from which said receiving means is spaced.

19. A shingle having a lock tongue on an edge thereof and a stop shoulder adjacent the base of the tongue, and tongue-receiving means wholly surrounded by the material of the shingle and spaced transversely from and in substantial transverse alignment with said lock tongue to receive a lock tongue of an adjoining shingle

and permit said lock tongue to be positioned underneath the first mentioned shingle adjacent said tongue-receiving means.

20. A surface covering comprising a plurality of elements laid in courses with adjacent elements engaged and adjacent courses in overlapping relation, said elements having a main body portion, a tab projecting from one end of the body portion and a notch formed by said projecting tab and the adjacent body portion, a slit adjacent the 10 opposite end of the body portion and spaced within the edges forming the most remote corner adjacent said notch, said slit, determining a partially connected section of the body portion for receiving a metallic securing means, said shingles 15 being secured to the underlying surface by metallic securing means passed through the partially connected sections of the elements and one element in a course covering said securing means and partially connected section of a second in the 20 same course, and having its tab underlying the second element adjacent said covered portions and said notch of the first element adapted to provide a stop for engagement of adjacent shingles.
